UNITED STATES PATENT OFFICE

2,244,909

RAZOR

Harry B. Griner, Delanco, N. J.

Application April 7, 1939; Serial No. 266,444

3 Claims. (Cl. 30—64)

My invention relates to razors and relates particularly to those razors wherein the blade is removable from the razor holder.

Heretofore, razor blades of both the flexible and rigid type have been used in holders. However, the blade holders require careful adjustment to tension or to hold the blade in position. When a man employing the razor is in a hurry or does not make the proper adjustment, the razor blade will not properly cut the hairs on a man's face.

Therefore, it is an object of my invention to provide a safety razor with an automatic blade tensioning unit.

Another object of my invention is to provide in a safety razor a device which will enable the razor blade to be quickly removed or rapidly installed in its proper position.

Another object of my invention is to provide a razor blade and razor blade holder which can easily be cleaned.

Another object of my invention is to provide a razor blade holder which will hold a non-flexing thin blade.

Other objects of my invention are to provide an improved device of the character described, that is easily and economically produced, which is sturdy in construction and which is highly efficient in operation.

With the above and related objects in view, my invention consists in the following details of construction and combination of parts, as will be more fully understood from the following description, when read in conjunction with the accompanying drawing, in which:

Fig. 1 is a fragmentary side elevational view of my invention showing a razor blade holder with a razor blade in place.

Fig. 2 is a fragmentary side elevational view of the razor blade holder showing the razor blade in position to be inserted.

Fig. 3 is a top view of the razor blade holder showing the razor blade in place.

Fig. 4 is a top view of a modification of my invention showing an assembled blade in the holder.

Fig. 5 is a side elevational view of Fig. 4.

Fig. 6 is a top view showing a modified razor supporting member holding a blade that has an inclined cutting edge.

Referring now in greater detail to the drawing, I show a razor with a hollow cylindrical handle, generally designated as A. A blade rest is generally designated as B. The blade rest consists of a substantially flat surface slightly in-

clined in relation to the handle, and attached to one side of the blade rest is a cylindrical member, generally designated as C, which interfits with the handle A. The blade holder or rest is of the safety type variety having a plurality of serrations in the front edge 10. It has two small end-stops 12 and 14 at each end in a position to receive the cutting edge of the blade. The stops 12 and 14 hold the blade in a predetermined position in the razor holder.

A razor blade, generally designated as D, has its cutting edge 16 lie over the serrations in order to cut into the beard without cutting the face of the user. The blade is positioned back of the serrations, as above described, and the serrations prevent the blade from cutting into the flesh of the user.

A plurality of side holding and overhanging lugs 17 and 18 prevent the side movement of the blade and also retain the blade in position in the holder by providing reaction against the locking pin, hereinafter described.

The rear end 22 of the blade, which comes substantially over the center line of the handle, 25 is contacted by a bevel or cylindrical lock pin, generally designated as E. The lock pin is beveled at its upper end 28 and is adapted to go up against the rear edge 22 of the razor blade in order to hold the razor blade securely in cutting position.

The cylindrical portion C of the blade holding member B has an inclined opening or inclined slot 24 therein at its lower end, which serves to receive a pin 23 that is fixed to and arranged to move the cylindrical portion 28 of the blade holding member longitudinally within the handle of the razor when the handle is rotated in relation to the blade holder member. A spring 25 surrounds the lower end of section 28 and impinges on the bottom 29 of the handle A and the lower end of the fixed blade cylinder C. Thus, the tendency of the spring 25 is to force the razor pin E in a downward direction.

The blade locking pin E is comprised of two cylindrical sections 26 and 28 which are connected by virtue of a spring 30 which is between the cylindrical sections 26 and 28. The lower section 28 of the locking pin E also is securely fastened to the handle A whereby rotation of the handle constitutes rotation of the lower cylindrical section 28.

The spring 30 serves to impose a substantially proper tension on the cone 28 of the lock pin E when the handle is rotated to allow the locking portion of the pin to extend beyond the blade

holding member and contact the blade. The spring 30 is suitably connected to the lower end of the section 26 and the upper end of section 28.

The spring 30 also serves to provide the proper tension on the blade when the blade is positioned in the blade holding member.

It will be noted that when the handle is turned in a counterclockwise direction or to the left-hand side as Fig. 1 is viewed with relation to the blade holding member that the locking portion of the lock pin is withdrawn into the inside of the cylindrical portion C of the blade holding member B. This allows the blade to be taken out of the holder.

When the blade is being inserted, the blade is placed in the holder, and the handle is turned in a clockwise direction in relation to the blade holding member. This draws the cylindrical portion of the blade holding member into the handle and allows the locking portion of the lock pin to project to a position where it engages the blade. In this position slight pressure is exerted on the spring 30. This insures proper tension on the blade without putting excessive tension on the same.

The lower end 28 of the locking mechanism is securely fastened into a plug 29. The plug 29 is in turn securely fastened to the casing of the handle. By this arrangement when the handle is rotated in relation to the blade holding member, the locking pin is also rotated with the result that the mechanical movements above described take place.

In Fig. 4 I have shown a modification of the blade portion of the safety razor wherein an assembled blade comprised of two parts is positioned in the holding member. A V-shaped member 30 is cut in the back edge of the blade, and at this point the locking pin engages the blade. Otherwise, the device is substantially as shown in Figs. 1, 2 and 3.

Fig. 5 is a side elevational view of the blade shown in Fig. 4.

Fig. 6 is a further modification of my device wherein the blade is on a slant in relation to the serrations on the edge of the blade holding member. This provides for a clear cutting edge when the blade is moved over the face.

The spring 25 is positioned within the hollow handle and surrounding the lower portion 28 of the locking mechanism. This spring is arranged to exert pressure between the plug and is in the bottom of the holder and the lower edge of the cylindrical portion of the blade holding member B. This spring is provided to force the blade holding member upwardly in the handle so that the locking pin will be withdrawn in relation to the blade holding member and the blade released as shown in Fig. 2.

Although my invention has been described in considerable detail, such description is intended as illustrative rather than limiting, since the invention may be variously embodied, and the scope of the invention is to be determined as claimed.

I claim as my invention:

1. A razor comprising a handle, a reciprocal movable blade-engaging member located within said handle, said member including two aligned sections, a spring connecting and interposed between each of said aligned sections, a cone-like end on one of said sections whereby said cone-like end may engage the blade for said razor, a spring interposed between said handle and said blade-engaging member whereby said spring tends to push said handle away from said blade-engaging member, a cylindrical blade-engaging member guide, and an interfitting pin and socket on said guide and said blade-engaging member for elevating or lowering said blade-engaging member whereby the razor blade is held or loosened.

2. A blade rest, a reciprocal blade-engaging member, a section having a bore, said section attached to said blade rest whereby said bore guides said blade-engaging member, said blade-engaging member including two aligned sections, a spring connecting and interposed between each of said aligned sections, a cone-like end on one of said sections whereby said cone-like end may engage the rear edge of the blade for said razor, a rotatable handle telescoping said guide, one of said sections fixed to said handle, means whereby said blade-engaging member may move into or from said bore guide in order to have the cone-like member engage the rear edge of said blade, and said cone-like member of the razor serving as substantially an adjusting cam for the blade.

3. A handle, a blade rest, a section having a bore, said section being attached to said blade rest and telescoping said handle, a reciprocal movable blade engaging member located within said handle, said member including two aligned sections, a spring interposed between and connecting each of said aligned sections, a cone-like end on one of said sections whereby said cone-like end may engage the rear edge of a razor blade, resilient means between said handle and one of said blade-engaging sections whereby said handle may be pushed away from said blade-engaging member, and a pin and slot connection interposed between said bore section and one of said aligned sections whereby said blade engaging member may be raised or lowered by the turning of said handle.

HARRY B. GRINER.
